DESIGN FOR A HANDBAG

Maurice J. Kruger, Kew Gardens Hills, N. Y., assignor to Kruger-Ressner, New York, N. Y., a co-partnership consisting of Maurice J. Kruger and Joseph Ressner

Application December 7, 1945, Serial No. 124,451

Term of patent 3½ years

(Cl. D87—3)

To all whom it may concern:

Be it known that I, Maurice J. Kruger, a citizen of the United States, residing at Kew Gardens Hills, Long Island, in the county of Queens, city, and State of New York, have invented a new, original, and ornamental Design for a Handbag, of which the following is a specification, reference being had to the accompanying drawing, forming part thereof.

In the drawing:

Fig. 1 is a front elevational view of a handbag, showing my new design;

Fig. 2 is a side elevational view thereof;

Fig. 3 is a top plan view; and

Fig. 4 is a bottom plan view.

I claim:

The ornamental design for a handbag, substantially as shown.

MAURICE J. KRUGER.
